UNITED STATES PATENT OFFICE.

JOSEPH H. HURDLE, OF MEBANE, NORTH CAROLINA.

MIXER.

Application filed October 19, 1926. Serial No. 142,665.

This invention relates to a mixer designed primarily for use by dentists for the purpose of thoroughly agitating and mixing alloys used in dentistry.

- 5   One of the objects of the invention is to provide a removable holder for receiving the amalgam and which is so mounted as to set up a rapid agitation of the contents of the holder.
- 10   A further object is to provide a device of this character which is simple and compact in construction and in which a small measured quantity of amalgam can be readily placed.
- 15   With the foregoing and other objects in view which will appear as the description proceeds, the invention resides in the combination and arrangement of parts and in the details of construction hereinafter described
- 20   and claimed, it being understood that changes in the precise embodiment of the invention herein disclosed may be made within the scope of what is claimed, without departing from the spirit of the invention.
- 25   In the accompanying drawings, the preferred form of the invention has been shown. In said drawings,
- Figure 1 is a front elevation of the mixer.
- Figure 2 is a side elevation thereof, a portion of the mechanism being shown in section.
- 30   Figure 3 is a view partly in elevation and partly in section of the means employed for gripping and agitating the holder, said holder being shown in position.
- Referring to the figures by characters of reference 1 designates an electric motor mounted on a suitable base 2. The shaft 3 of the motor has a disk 4 keyed or otherwise attached to one end thereof and arranged on one face of this disk is a wrist pin 5 extending through a slot 6 formed in one arm of a lever 7. This lever is fulcrumed on a post 8 extending from the housing of the motor and the other arm of the lever is extended into and formed with or secured to a spring yoke 9 the terminals of which are formed with spring arms 10 projecting beyond the end of
- 35   the lever. The terminal portions of these arms 10 are recessed as at 11 so as to constitute gripping jaws and the intermediate portion of the yoke 9 constitutes a rest as shown at 11 for the intermediate portion of a holder 13. This holder is preferably in the form of a capsule of gelatin or any other desired material, the parts of the capsule being readily separable for the purpose of placing within the capsule a measured quantity of alloy. After the alloy has been placed within the capsule and the capsule has been closed by 60 telescoping the members together, the jaws 11 are swung apart and the capsule inserted between them with its ends resting within the recessed jaws and the intermediate portion supported by the rest 12. An electric current is then directed to the motor with the result that shaft 3 will be rotated at a high speed and lever 7 will be rapidly oscillated, setting up a rapid back and forth motion of the capsule and the contents thereof with 70 the result that said contents will be thoroughly mixed.
- 40   What is claimed is:
- A mixing attachment for an electric motor including a disk for attachment to the shaft 75 of a motor, a wrist pin extending therefrom, a lever having a longitudinal slot in one end portion through which the wrist pin extends, a pivot member extending through the lever beyond the periphery of the disk, a yoke straddling that end of the lever remote from the slot, said yoke constituting means for supporting the middle portion of a capsule, the side portions of the yoke being extended toward the pivot of the lever away from the 80 end thereof, and a spring arm extending from each side portion of the yoke outwardly past and spaced from the yoke, each arm having a recess in its free end portion, and a capsule insertable laterally between the spring 85 arm into position on the yoke and in the recesses.
- 45   In testimony that I claim the foregoing as my own, I have hereto affixed my signature.

JOSEPH H. HURDLE.
